EX

OR D 611

Design No. 611

S.F. Moore's Stove.

Patented November 29, 1853 -

Dec. 6/1

Simon F. Moore of Batavia, N.Y.
Letters Patent No. 611. Dated Nov. 29th, 1853.

The schedule referred to in these Letters Patent, and making part of the same.

To all whom it may concern:

Be it known that I, Simon F. Moore, of Batavia in the County of Genesee and State of New York, have invented a new and useful design for Elevated Oven Cooking Stoves; and I do hereby declare that the following is a full, clear, and exact description of such design:

I; all the doors for the stove and oven are constructed with plain panels and mouldings, at once neat appropriate and handsome, and which I claim to be superior in these respects to any other figures of like character used upon cooking stoves, and also more durable and easy to be kept clean and in order.

II; the plain and unornamented surface of the front and sides of the stove which are very suitable and appropriate for such a purpose, and render it an easy task to keep the stove clean and bright.

Reference being had to the annexed drawing marked No. 1, which forms a part of this specification, such drawing exhibits a perspective view of an elevated oven cooking stove with my design upon it.

I disclaim all other or further claim in the premises beyond the design herein set forth.
